UNITED STATES PATENT OFFICE.

EDMOND STOCQ, OF NEUILLY-SUR-SEINE, FRANCE.

DEVICE FOR DRIVING STONE AND MARBLE SAWING BLADES.

Application filed January 21, 1922. Serial No. 530,934.

To all whom it may concern:

Be it known that I, EDMOND STOCQ, a subject of the King of Belgium, residing in Neuilly-sur-Seine, France, have invented 5 new and useful Improvements in Devices for Driving Stone and Marble Sawing Blades; and I do hereby declare the following to be a full, clear, and exact description of the invention, such as will enable others 10 skilled in the art to which it appertains to make and use the same, reference being had to the accompanying drawings, and to letters or figures of reference marked therein, which form a part of this specification. 15

This invention relates to improvements in stone sawing machines, such as the saw frames holding the blades utilized for sawing stone, marble, the object of the invention being to effect improvements whereby at the end of each stroke the shock is taken over and imparted again to the return stroke, so transmitting the kinetic energy of the frame; the driving parts are 20 freed from any shocks or other drawbacks derived from the inertia of the frame; the driving means is so constructed as to be capable of modifying its stroke and of so regulating the stroke and the speed of the 25 machine as to balance and equalize the effort; as hereinafter described and claimed.

The invention has been represented in the accompanying drawings which are intended to serve as mere examples that do not restrict the invention to the one form of execution shown and described in this specification. 30

In these drawings:

Fig. 1 shows a saw frame as seen from the 40 drive side.

Fig. 2 is a sectional view through the median plan of the driving gear, assuming the frame to have stopped its motion.

Fig. 3 is a sectional view similar to that 45 of Fig. 2 but when the frame has reached the end of its stroke.

Fig. 1 shows that the frame motion is controlled by crank-shaft A supported in two bearings B and B' and that the slides 50 C and C' which carry the frame through bushes D and D' are fixed to a cross beam E to which the driving gear is attached by means of the bearings B and B' and consequently follows the frame in all its ascending and descending moves.

The frame is further connected with

slides C and C' at the bottom by tubular boxes containing springs G only one of which is shown intended for attenuating and then taking over the impact, said boxes 60 being swivelled at H and H' so as to accompany the frame all through its oscillations.

The box containing the springs G can be seen in section.

Fig. 2 shows a sectional view through the middle of drive shoe K; in this view the frame is supposed to be at rest or at mid stroke. This shows that the swivel or crank A will transmit the driving motion through box L which carries shoe K sliding up and down along sliding track I fixed to the frame.

That box L has been mounted upon springs M and M', its sliding motion in shoe K imparts to the frame a stroke the length of which is automatically modified in accordance with the resistance met with by the driving gear when driving the frame. This arrangement permits a starting motion of 75 the frame at the rate of a very short stroke the length of which automatically varies owing to the actual inertia of the frame as its speed is gradually increasing. The whole device is in practice constantly bathed 80 in oil by suitable means.

Fig. 3 shows the frame reaching the end of its stroke. The springs G and G' acting as buffers and collectors of inertia force (only one of them being shown in the figure) are pressed down as a result of the motion of the frame; they therefore stop this motion and, on being released, they impart to the frame a backward swing so causing it to take over the energy with which they had been pressed and tightened. A similar operation takes place at the other end of the stroke.

The above mentioned yielding drive acts to the effect of equalizing the oscillations of the frame and making up for the loss of energy due to the friction of the mechanisms and of the saws when these latter are cutting the material in question (marble, stone, etc.).

It should be understood that the types herein set forth and described as regards both drive and buffer arrangements are merely indicated by way of examples free from any restriction, effect so that any pneumatic or other buffer arrangement for the purpose of deadening the shocks, as also

any other method for so driving the machine as to secure the same result can be employed without departing from the principle of this invention.

5 The advantages of the system forming the subject matter of this invention are as follows:

1. Considerable saving on motive power, as the driving gear no longer stops the frame reaching the end of its stroke in order to impart to it the sudden backward motion which was necessary, so that the consumption of power is confined to such amount as is necessary for overcoming the friction of the saw blades on the stone as well as the friction taking place in the various mechanisms and for overcoming the inertia of all the moving members at the time of reversal.

20 2. Substantial reduction of the sizes of the driving parts, as these are no longer subject to the inertia strain exerted by the frame when reaching the end of its stroke and have merely to correspond to the amount of power which must be transmitted and which, as stated in the preceding paragraph, has also been greatly reduced.

25 3. Possibility of constructing in a practical manner sawing frames provided with

a driving gear to be directly placed upon the columns or the frame work of the machines so securing the advantage of considerably reducing the amount of room necessary for erecting these machines.

Claim.

In a machine of the class described, a frame mounted for rocking movement, a driving shaft having fixed bearings and a crank, a second frame pivotally connected with the rocking frame, yieldable means active to progressively resist relative angular movement of the rocking frame, a guide element attached to the second frame, a box mounted for reciprocating movement in the guide element, a shoe mounted on the wrist of the crank and also mounted for reciprocating movement in the shoe at right angles to the plane of movement of the box in the guide element, and yieldable means active to progressively resist movement of the shoe in the box in either direction.

35 In witness whereof I affix my signature.

EDMOND STOCQ.
